UNITED STATES PATENT OFFICE

EARL N. WHITE, OF LOS ANGELES, CALIFORNIA

FIXTURE FOR SHOW CASES

Application filed August 17, 1928. Serial No. 300,215.

This invention has to do with a fixture for use in a show case, or the like, and it is a general object of the invention to provide a device which is simple and convenient and which will effectively carry and display products within a show case.

Merchants carry various products in glass show cases. In the case of food products, for instance meats, the show cases are provided with refrigerating means, and in practice more or less inconvenience is experienced in handling the meats within the cases. Further, butchers frequently carry other products which could be advantageously carried in a show case but which are ordinarily located on top of the case or in a remote part of the case to avoid interference with the handling of the meats. I will refer, for example, to cottage cheese and brick cheese as products of this character.

It is a general object of my present invention to provide a fixture for use in a show case whereby products of various kinds can be carried in the case in a neat and convenient manner and without interference with the products ordinarily arranged in the case.

Another object of the invention is to provide a device or fixture of the character mentioned which can be operated to a position at the exterior of the case so that products or articles carried by it can be conveniently handled.

A further object of the invention is to provide a device of the character mentioned which is of simple, inexpensive construction and which is simple and convenient to operate.

The various objects and features of my invention will be best and more fully understood from the following detailed description of a typical form and application of the invention, throughout which description I refer to the accompanying drawings, in which:

Fig. 1 is a view of the rear of a typical

show case showing the doors providing access to the interior of the case. Fig. 2 is an enlarged detailed plan section taken as indicated by line 2-2 on Fig. 1 and showing a fixture embodying the present invention in position in the case. Fig. 3 is a view similar to Fig. 2 showing one door of the case open and a part of the fixture extended or positioned to project from the case. Fig. 4 is a view similar to Fig. 3 showing another door of the case open and another part of the fixture swung to a position to project from the case. Fig. 5 is a view taken substantially as indicated by line 5-5 on Fig. 2. Fig. 6 is an enlarged detailed sectional view taken as indicated by line 6-6 on Fig. 2. Fig. 7 is an enlarged detailed sectional view taken as indicated by line 7-7 on Fig. 5.

The device or fixture provided by this invention may be advantageously used in various situations and for handling various products or articles. I will, for purpose of example, describe a typical form of the invention suitable for use in an ordinary type of show case for handling products such as I have referred to above, it being understood that such specific reference is not to be construed as limiting or restricting the scope or range of the invention.

The show case illustrated in the drawings is of the type ordinarily used in butcher shops, or the like, and includes, generally, a glass front 10, a glass top 11, a plurality of doors 12, in the back providing access to the interior of the case, and various other parts common to construction of this nature. The frame construction provided at the back of the case may be of wood, or the like, and may include one or more vertical posts 13 on which the doors are hung or to which the doors latch when closed. In the arrangement illustrated each post 13 intermediate the ends of the case has a door 12 hinged to it and extending in one direction and has another door latched to it, the latter door being arranged to extend to

the post from the opposite direction. The doors are shown mounted by means of hinges 14 and are releasably held in closed position by latches 15.

5 The fixture provided by this invention includes, generally, a plurality of arms to be normally positioned within the show case, mounting means for the arms, and carriers on the arms to carry articles or products to be held by the fixture. In the particular case illustrated, I have provided an arm 16 supporting a carrier 17 adapted to handle a tray, or the like, and two arms 19 and 20 supporting carriers 21 and 22, respectively, adapted 10 to carry boards 23 supporting bricks of cheese, or the like. The several arms 16, 19 and 20, are carried by a single mounting means or bracket 24 to be mounted in the show case in a manner such as I have illustrated 15 throughout the drawings.

15 The mounting bracket 24 has a base 25 to be attached to a part of the case by screws 26, or the like, and has spaced projecting flanges 27 which carry a pivot pin 28. In the preferred application of the device the base 25 is mounted on the inner side of one of the 20 posts 13 of the show case and the mounting is such as to permit the base with its connected parts to be detached from the post of the case. In the construction illustrated I have shown spaced screws 26 applied to the post of the case and I have shown the base 25 provided with slots 29 to receive the screws and with enlarged openings 30 at the lower ends 25 of the slot to pass the heads of the screws so that the base can be arranged on the screws. The flanges 27 of the mounting bracket are spaced apart vertically and project horizontally from the base 25 to carry the pivot pin 30 28 and support the arms, as will be herein-after described.

35 The arm 16 is arranged on the upper end portion of the pivot pin 28 to be supported on the uppermost flange 27 of the mounting bracket. The carrier 17 provided for carrying a tray 18, or the like, is a rectangular frame-like structure mounted on the outer end of the arm 16. The carrier 17 projects outwardly and laterally from the arm 16 and 40 is shaped and proportioned to receive a tray 18 in the manner illustrated throughout the drawings. I have shown a tray 18 which fits or seats in the carrier 17 and which is provided at its rim with a projecting lip or 45 flange overhanging the carrier. The carrier 17 is capable of supporting a tray 18 of considerable size in which case it is desirable to provide means for bracing the parts so that they will properly handle a loaded or filled 50 tray.

55 In the case illustrated I have shown a brace 31 extending downwardly from the outer end portion of the arm 16 and I have shown a brace 32 connecting to the carrier at a point 60 substantially removed from the point of en-

gagement between the arm and the carrier. The lower ends of the braces 31 and 32 are joined and are carried on the lower portion of the pivot pin 28 to be supported by the lowermost flange of the mounting bracket.

70 The arm 16 carrying the tray 18 is not very long, however it is sufficiently long and so arranged with reference to the carrier as to enable the carrier to be swung from within the case to a position where it projects from the case, as illustrated in Fig. 3. The arm supports the carrier 17 far enough from the mounting bracket to permit the carrier to be swung or operated past the post 13.

75 The arm 19 is comparatively long and is mounted on the pivot pin 28 to be supported by the flange 27 which supports the middle portion of the pin. The arm 19 is of considerable length in order to accommodate the arm 20 and carrier 22, as will be hereinafter 80 described.

85 The carrier 21 is supported by the outer portion of the arm 19 and projects laterally from the arm 19. The carriers 17 and 21 project in opposite directions from the arms 16 and 19 as will be apparent from inspection of the drawings. The carrier 21 is a rectangular frame structure and in the case illustrated it is fitted with pins 36 for supporting boards 23, or the like, carrying bricks of 90 cheese or any other product.

95 The arm 20 is similar to the arm 19 except that it is shorter. The arms 19 and 20 are carried at the same point on the pivot pin 28, and to permit this arrangement they have 100 meshing parts 38 engaging the pin as shown in Fig. 7 of the drawings. The arms 19 and 20 are related so that they may be arranged together, side by side, or may be separated or moved independently. The carrier 22 is 105 similar to the carrier 21 and is mounted on the outer end portion of the arm 20 to project in the same general direction as the carrier 21. The carrier 22 is located on the arm 20 so that it is parallel to and adjoins the carrier 21 when the arms 19 and 20 are together as 110 shown in Fig. 3. The parts are proportioned so that the carrier 22 is spaced a substantial distance from the mounting bracket permitting the carrier to be swung past the post 13 of the case in a manner such as is illustrated 115 in Fig. 4.

120 In using the device the mounting bracket is mounted on the inner side of a post 13 of the show case as shown throughout the drawings, and when not in the use the parts are arranged as shown in Fig. 2. In this case the two carriers 21 and 22 are arranged side by side with reference to each other and are arranged end to end with the carrier 17. It 125 is to be particularly noted that the carrier 17 projects in one direction laterally with reference to the arms, while the carriers 21 and 22 project in the opposite direction laterally, with reference to the arms. The mounting 130

bracket is preferably located on the post 13 of the case so that the carriers are supported as close as possible under the top 11 of the case in order to permit articles to be arranged in the case in the usual manner. When it is desired to remove contents from the tray 18, the door of the case opposite the tray is opened and the tray is swung to the extended or out position as shown in Fig. 3. The tray when thus operated to the extended or out position, is at the exterior of the case allowing the contents of the tray to be conveniently removed. It is to be noted that this operation of the device does not in any way distract or interfere with the positioning of the arms carrying the carriers 21 and 22. When the tray is no longer desired in the out position, it can be swung back to the position shown in Fig. 2, and the door of the case closed. To handle the products or articles carried by the carriers 21 and 22, the door opposite the carriers 21 and 22 is opened and the parts are swung to a position such as is shown in Fig. 4. It will be apparent that the arrangement of the arms 19 and 20 permits the arm 20 being operated independently of the arm 19 and permits the carriers 21 and 22 being operated so that the articles on the two carriers can be handled without interference with each other. When not in use, the carriers 21 and 22 can be swung back to the in position shown in Fig. 2 and the door of the case closed.

From the foregoing description it will be apparent that I have provided a fixture which can be easily and conveniently handled and which operates to increase the capacity of a show case and also its display value. Further, it will be obvious that the device is of simple, inexpensive construction and is such that it can be very easily removed from the case whenever desired.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A fixture of the character described including, two arms, mounting means pivotally carrying the arms to swing horizontally, and a carrier on each arm, the carrier on one arm being arranged to project laterally from one side of the arm in a direction opposite from which the other carrier projects from the other arm.

2. A fixture of the character described including, two arms, mounting means pivotally carrying the arms to swing horizontally, and a horizontally disposed carrier on each arm, the carrier on one arm being arranged to project laterally from one side of the arm

in a direction opposite from which the other carrier projects from the other arm.

3. A fixture of the character including, two horizontally disposed arms, mounting means pivotally carrying the arms to swing horizontally, and a horizontally disposed carrier on each arm, the carrier on one arm being arranged to project laterally from one side of the arm in a direction opposite from which the other carrier projects from the other arm.

4. A fixture of the character described including, an arm, a base plate, a pivot pin carried by the plate to hold the arm, a carrier projecting laterally from the outer end portion of the arm, and braces between the carrier and arm and the pivot pin.

5. A fixture of the character described including, an arm, a mounting pivotally carrying the arm, and a carrier on the outer portion of the arm projecting laterally from only one side thereof, the carrier being in the form of a frame for carrying a tray.

6. A fixture of the character described including, a mounting to be applied to a case, three arms projecting from the mounting, a carrier projecting laterally from the outer portion of one arm, and two carriers arranged side by side and one carried by each of the other arms and projecting laterally therefrom in a direction opposite from which the first mentioned carrier projects from the first mentioned arm.

7. In combination, a case having a post and a door, an arm, a pivotal mounting for the arm, means for detachably mounting the pivotal mounting on the post within the case, and a carrier projecting laterally from the arm and operable from a position entirely within the case to a position where it projects from the case through the door opening.

8. In combination, a case having a post and a door swung thereon, an arm, a pivotal mounting for the arm on the post within the case, and a carrier projecting laterally from the arm so that it is spaced from the mounting and operable from a position entirely within the case to a position where it projects from the case through the door opening.

9. In combination, a case having a post and doors at either side of the post, two arms, means pivotally connecting the arms with the inner side of the post, and carriers projecting laterally in opposite directions from the two arms to be operable from positions entirely within the case to positions where they project outwardly through the door openings.

10. In combination, a case having a post and doors at either side of the post, two arms, means pivotally connecting the arms with the post, and a carrier on each arm, the carrier on one arm projecting laterally from its arm in a direction opposite from which the other carrier projects laterally.

from the other arm, the carriers being operable from positions entirely within the case to positions where one carrier projects outwardly at one side of the post and the other carrier projects outwardly at the other side of the post.

11. A fixture of the character described including, an arm, a mounting pivotally carrying the arm, and a carrier on the outer portion of the arm projecting laterally from only one side thereof, the carrier being provided with means for carrying a tray.

In witness that I claim the foregoing I have hereunto subscribed my name this 26th day of July, 1928.

EARL N. WHITE.
